UNITED STATES PATENT OFFICE

2,572,769

AUTOMATIC ADJUSTABLE RAIL BRACE

Arthur R. Schulze, Youngstown, Ohio, assignor to
United States Steel Company, a corporation of
New Jersey

Application August 12, 1949, Serial No. 109,980

3 Claims. (Cl. 238—292)

1

This invention relates to an automatic adjustable rail brace and is a continuation-in-part of my copending application, Serial No. 5,920, filed February 3, 1948, which has matured into Patent No. 2,525,185, dated October 10, 1950.

In adjustable rail braces most commonly used at present, the locking means are either horizontal or vertical threaded bolts and/or cotter pins. Adjustment requires loosening or removing the nuts from the bolts or removing the cotter pins. The bolts are frequently corroded with the nuts seized on the bolts. Loosening or removal then causes damage which requires the replacement of either the nut or the nut and bolt. Cotter pins must necessarily be replaced. An adjustable rail brace is one in which means are provided for maintaining the brace in tight engagement with the rail as wear and corrosion of the parts occur.

It is an object of my invention to provide a rail brace which is automatically adjustable.

This and other objects will be more apparent after referring to the following specification and attached drawings, in which:

Figure 1 is a plan view of my invention;

Figure 2 is a sectional view taken on the line II—II of Figure 1;

Figure 3 is a sectional view taken on the line III—III of Figure 1;

Figure 4 is a view, partly in section, showing the wedge in retracted position;

Figure 5 is a plan view of a second embodiment of my invention; and

Figure 6 is a sectional view taken on the line VI—VI of Figure 5.

Referring more particularly to the drawings the reference numeral 2 indicates a tie plate which is provided with a seat 4 for the rail 6. Spaced from the rail at one side thereof, is a longitudinal stop 8 which is welded or otherwise fastened to the tie plate 2. The stop 8 is arranged at an angle to the center line of the rail 6 as best shown in Figure 1. An adjustable brace 10 has one end contacting the head of the rail as shown in Figure 2, and the other end resting on a wedge 12. The end 14 of the brace 10, which fits under the railhead, is curved as shown and the lower end 16 is also curved and rests in a curved pocket 18 in the wedge 12. An inverted U-shaped member 20 is fastened to the top of the stop 8 by means of bolts 22 which pass through flanges 24 of the U-shaped member. The under surface 26 of the member 20 is arranged at an angle as shown in Figure 2, which angle is greater than the angle of the rail base. Because of this angle, the spring clip 28 is always

2

urged toward the center line of the rail. A spring clip 28 passes through the opening in the U-shaped member 20 and through an opening 30 in the brace 10. One end of the clip 28 bears on the base of the rail and the other end is received in a slot 32 in the tie plate 2. A longitudinal opening 34 extends substantially throughout the length of the wedge 12. A hole 36 extends from the outside of the narrow end of the wedge to the opening 34, the hole 36 being considerably smaller in section than the opening 34, so that a shoulder 38 is provided. Welded to the tie plate 2 within the opening 34 is a stop lug 40 having a slot 42 in the upper end thereof which is provided with a counterbored portion 44. This counterbored portion provides a transverse abutment which serves as a bearing for a spring cone 46. A spring 48 extends from the abutment 38 to the spring cone 46.

The device is assembled and functions as follows:

A bolt 50 is passed through the hole 36 and the coil spring 48 and is threaded into the spring cone 46 with the bolt head bearing against the forward end of the wedge so that the spring is compressed as shown in Figures 1 and 4. The adjustable brace 10 is then placed with its top end 14 bearing against the head of the rail and its lower end 16 in the groove 18. The spring clip 28 is then placed in position with the inverted U-shaped member 20 thereover. The bolt 50 is then removed, permitting the spring 48 to expand between the spring cone 46 and abutment 38, thus urging the wedge 12 away from the stop lug 40. This movement of the wedge forces the rail brace 10 against the rail, since the rail brace cannot move longitudinally because of the contact of the spring clip 28 with the sides of opening 30. However, transverse movement of the brace 10 is permitted since the width of the opening 30 is greater than the space occupied by clip 28. The thrust line 52 of the brace 10 between the rail 6 and the wedge 12 is within the base width of the wedge so that there is no tendency for the wedge to overturn. The end of the spring clip in conjunction with the groove 32 retains the spring clip at right angles to the rail. When a train passes over the rail 6 vibration occurs and during this time the spring 48 will force the wedge 12 longitudinally in the direction of the narrow width thereof, thus automatically adjusting the rail brace.

In the embodiment shown in Figures 5 and 6, the spring clip 28 is eliminated, but the wedge 12, stop 8, the spring 48 and associated parts are the

same. However, the brace 10 is replaced by a brace 54 having a substantially horizontal portion 56 thereon. A hole 58 is provided in this horizontal portion 56. The top portion 60 of the brace 54 is rounded and rests against the railhead. The bottom end 62 of the brace 54 is also rounded and rests in the groove 18 on the wedge. The brace 54 is provided with spaced apart ribs 63, each of which has its bottom portion 64 shaped to conform to the top of the base 10 of the rail. A bolt 66 passes through the tie plate 2 and the hole 58 in the brace 54. A cotter pin 68 passes through openings in the bolt 66 and nut 70 to hold the nut spaced from the brace 54. The brace is assembled and functions in substantially the same manner as that of the first embodiment.

While two embodiments of my invention have been shown and described, it is apparent that other adaptations and modifications may be made without departing from the scope of the following claims.

I claim:

1. An automatic adjustable rail bracing device comprising a tie plate having a seat portion for the base of the rail, a stop member fastened to the tie plate and spaced from said rail, an adjustable brace bearing against the rail and extending in the direction of the stop member from the rail toward the tie plate, means for limiting longitudinal movement of the brace, means for limiting vertical movement of the brace, said stop member and brace being separated to provide a space therebetween which is wider at one end than at the other, a wedge in said space bearing against said stop member and against said brace to hold the brace against said rail, said brace having its lower end resting on said wedge and its upper end beneath the rail head whereby vertical movement of the wedge is limited, said wedge having a longitudinal downwardly facing opening therein terminating in a transverse abutment adjacent the narrow end, a relatively stationary transverse abutment in said space adjacent the wide end thereof, and a spring in said longitudi-

45

nal opening bearing against both of said abutments to urge the wedge longitudinally in the direction of its narrow end, and hold down means for holding said rail on said tie plate.

5 2. An automatic adjustable rail bracing device according to claim 1 in which the means for limiting longitudinal movement of the brace and the hold down means for holding the rail on said tie plate includes an inverted U member fastened to said stop, the underside of said inverted U member sloping downwardly away from the rail to form an abutment, said brace having an opening therein adjacent its lower end, and a spring clip extending through the inverted U member and bearing against said abutment with one end bearing on the base of the rail and the other end bearing on the tie plate, the width of the opening in the brace being substantially the same as the width of the clip.

15 3. An automatic adjustable rail bracing device according to claim 1 in which the means for limiting longitudinal movement of the brace and the hold down means for holding the rail on said tie plate includes a substantially horizontal portion 25 on said brace, said horizontal portion having a hole therethrough, a rib on said brace extending downwardly substantially to the base of the rail, a bolt passing through said last named opening and through an opening in the tie plate, 30 and a nut fastened to said bolt above said horizontal portion.
